DESIGN FOR A SLIPPER

Morris Greenberg, New York, N. Y.

Application December 11, 1945, Serial No. 124,610

Term of patent 3½ years

(Cl. D7—7)

To all whom it may concern:

Be it known that I, Morris Greenberg, a citizen of the United States of America, residing in New York, county of New York and State of New York, have invented a new, original, and ornamental Design for a Slipper, of which the following is a specification, reference being had to the accompanying drawing, forming part thereof.

The figure on the drawing is a front perspective view of a slipper showing my new design. The opposite side presents substantially the same appearance as the side shown.

I claim:

The ornamental design for a slipper, substantially as shown and described.

MORRIS GREENBERG.
